CLAIM

The ornamental design for a magnetic phone holder, as shown and described.

DESCRIPTION

FIG. 1 is a front, left and top perspective view of a magnetic phone holder showing my new design in a first configuration of use;

FIG. 2 is a rear, right and bottom perspective view thereof;

FIG. 3 is a perspective view of the magnetic phone holder in a second configuration of use;

FIG. 4 is a top plan view of the magnetic phone holder in a third configuration of use;

FIG. 5 is a left side view of the magnetic phone holder in a fourth configuration of use;

FIG. 6 is a front view of the magnetic phone holder of FIG. 1;

FIG. 7 is a rear view thereof;

FIG. 8 is a left side view thereof;

FIG. 9 is a right side view thereof;

FIG. 10 is a top plan view thereof; and,

FIG. 11 is a bottom plan view thereof.
